China Patent Application No. 201780072126.1 filed May 22, 2019 entitled "Cooler".[‡]

(Continued)

Primary Examiner — Michael A. Pratt

(74) *Attorney, Agent, or Firm* — Dinsmore & Shohl LLP

CLAIM

The ornamental design for a latch, as shown and described.

DESCRIPTION

Cross-reference is made to U.S. Design patent App. Ser. No. 29/585,272 titled "Cooler." filed Nov. 22, 2016, and U.S. utility patent App. Ser. No. 15/819,950 titled "Cooler", filed Nov. 21, 2017, all of which are expressly incorporated herein by reference.

FIG. 1 is a front perspective view of a first embodiment of a latch design;

FIG. 2 is a front elevation view of the design of FIG. 1;
FIG. 3 is a rear elevation view of the design of FIG. 1;
FIG. 4 is a left side elevation view of the design of FIG. 1, with the right side elevation view being a mirror image of FIG. 4;

FIG. 5 is a top plan view of the design of FIG. 1;

FIG. 6 is a bottom plan view of the design of FIG. 1; and, FIG. 7 is a front perspective view of a second embodiment of a latch design.

The broken lines shown in the latch are for portions that forms no part of the claimed design.
